Application October 30, 1950, Serial No. 192,993

10 Claims. (Cl. 264—15)

1

This invention relates to centrifugal mechanism and more particularly to such mechanism of the type used for operating switches adapted to control the starting windings of dynamoelectric machines.

The use of centrifugal mechanism mounted on the shaft of a dynamoelectric machine to operate a switch for disconnecting the starting windings after the machine has come up to a certain speed, is well known. In order that there will be no sparking at the contacts, it is necessary that the contacts be separated with a snap action. In order to get this snap action, prior mechanisms have been rather complicated in construction and required a number of complicated parts.

An object of the present invention is to provide an improved centrifugal mechanism for operating a switch with a snap action.

Another object of the present invention is to provide an improved switch operating centrifugal mechanism for use on a rotatable shaft.

The above and other objects of the present invention are accomplished by providing a support or plate fixed to the shaft and having a weighted member pivoted to the plate and a sleeve located on the shaft and adapted for sliding axial movement on the shaft. A coiled spring is located around the pivot of the weight and has one portion engaging the weighted member and another portion engaging the plate. The sleeve which is adapted to operate the switch is moved by a U-shaped lever made of music wire. This lever is pivoted on the pivot of the weighted member and has portion embracing lugs on the sleeve. A pair of springs are connected to the weighted members and to the yoke and are normal beyond the dead center of the pivot member for the weights. These weights are adapted for pivotal movement under the action of centrifugal force in response to the rotation of the shaft and move the spring to the other side of dead center against the force of the first mentioned spring and causes the lever to shift the sleeve to another position and operate the switch at a predetermined speed of the shaft.

Further objects and advantages of the present invention will be apparent from the following description, reference being had to the accompanying drawing wherein a preferred embodiment of the present invention is clearly shown.

In the drawing:

Fig. 1 is a fragmentary sectional view of a 55 the stationary contact 27. The arm 29 is pro-

2

dynamoelectric machine and showing in detail the centrifugal mechanism in its normal state.

Fig. 2 is a view similar to Fig. 1 but showing the centrifugal mechanism in its operative position.

Fig. 3 is a top plan view of the mechanism looking in the direction of arrow 3 of Fig. 1.

Fig. 4 is a sectional view taken on line 4—4 of Fig. 3.

10 Fig. 5 is an end view of the mechanism taken on line 5—5 of Fig. 1.

Figs. 6, 7, and 8 are top, end, and side views, respectively of the shifting lever used in the present invention.

15 Fig. 9 is a fragmentary sectional view illustrating the formation of a stop on the plate 40.

Referring to the drawing there is shown a fragment of an end member 20 of a dynamoelectric machine. A rotor 21 of any standard 20 construction is mounted on a shaft 22 which is rotatably mounted in a bearing surface 23 provided by the end member, only a fragment of the rotor is shown. The machine is provided with a single-phase main field winding a starting field winding, not shown. These windings are mounted in the conventional manner.

It is well known in the art that in a single phase induction motor having separate starting and running windings, it is desirable that 30 the starting field exciting windings should be energized during the period when the motor starts from a standstill, or under operating conditions that the speed of the motor is reduced below a predetermined value. It is also desirable that the starting field exciting windings should be deenergized when the speed of the motor exceeds a predetermined value. In order to accomplish this result, there is provided a switch 25 mounted on a switch support 26 made of insulating material which is secured to the end member 20. The switch is provided with electrical contacts 27 and 28 which are connected to the energizing circuit of the starting field exciting winding.

45 Referring to Figs. 1 and 2, the stationary contact 27 is adapted to be connected to the stator winding of the motor, not shown. This stationary contact 27 is normally engaged by the movable contact 28 carried by an arm 29, which is pivotally secured to a stud screw 30 attached in the end frame 20 of the motor. A spring 31, disposed between the arm 29 and the frame 20, yieldably urges the arm 29 so that its contact 28 is moved out of engagement with

vided with rubbing blocks 32 adapted to be engaged by a switch actuating sleeve 33, made of insulating material, which is slidably mounted on the shaft 22. The sleeve is urged against the rubbing blocks 32 by centrifugal device 35 attached to the shaft 22.

The centrifugal device 35 of the present invention comprises a governor back or plate 40 punched from sheet metal and then operated on to form a central tubular portion or flange 41 which may be connected to the shaft in any suitable manner, preferably by a press fit so that the plate is rotatable therewith. As viewed in Fig. 3 the upper side of the plate has two apertured ears 42 on opposite sides thereof to receive a cross pin 43 having annular grooves adjacent its ends. A U-shaped cradle 44 pivots on the pin 43 with its side arms 45 positioned outside of the ears 42 of the plate. The ends of the side arms are provided with a notch to provide flat surfaces 46 and 47 which cooperate with a stop 48 on the plate to limit the pivotal movement of the cradle 44. The formation of the stop 48 on plate 40 is clearly illustrated in Fig. 9. A centrifugal weight 49 is attached to the yoke of the cradle 44. A spring 50 having two coiled portions encircles the pin 43 with the ends 52 lying against the top of the plate 40 and with a central bowed portion 53 engaging the weight 49 to urge same and the cradle inwardly until the surface 47 contacts with the stop 48 as clearly shown in Figs. 1 and 4. The outward movement of the cradle and weight takes place against the tension of the spring 50.

The sleeve 33 is slidable on the shaft 22 between the plate 40 and a C-washer 55 fitted in a groove on the shaft 22. This sleeve is formed with integral diametrically opposed lugs 56 which are embraced by a portion of a U-shaped lever 60 so that upon pivotal movement of the weight cradle 44 about the pin 43 as the axis, the sleeve 33 will be moved axially along the shaft 22. The lever 60 as shown in its preferred form is made from a single length of music wire of suitable stiffness and of uniform diameter and is so formed as to provide bowed or arched portion 61 and from the opposite ends of the arched portion 61 horizontal loops 62 are formed in the same plane as the arched portion. These loops extend downwardly from the arched portion. The lower ends of the loop portions continue and are bent so as to provide parallel arms 63. The arms 63 are formed with an actuating loop element 64. These loop elements 64 are so placed that they will embrace the lugs 56 as shown in Figs. 1 and 2. The free ends of the arms 63 are formed with hooks 65. These hooks are open and of such size and shape that they will snap into the annular grooves formed adjacent the ends of the pin 43 and will hold the pin in assembled relation with the plate 40. When the hooked ends 65 of the lever 60 are attached to the pin 43, the loop portions 64 will embrace the lugs 56 and the arched portion will be extended above the collar 41. The cradle 44 is provided with ears 66 struck out from each arm. A hole is provided in each ear into which an end of a spring 67 may be hooked. The other end of the spring 67 is hooked through the loop 62 in the lever 60. The springs 67 when in their normal position exert a force which causes the side 64a of the loop 64 to bear against the lug 46 to urge the sleeve 33 to the right to close the contacts 27 and 28 and the spring 67 will be below the axis of pin 43.

In operation of the mechanism the switch as shown in Fig. 1 is in a closed position, corresponding to the position when the rotor is idle or running at slow speeds. In this position the contact 28 engages contact 27 and the actuating member or sleeve 33 is exerting a pressure on the rubbing blocks 32 of arm 29 due to the effect of springs 67. When the main circuit through the motor is closed the rotor will start to rotate. As the rotor 21 increases in speed consequently the centrifugal force acting on cradles 44 is increased. This results in tensioning the springs 50 and 67 and causes the ends of the spring 67, which are hooked over the ears 66, to move outwardly with the cradle 44. This results in expanding the springs 67. As the motor increases its speed the springs 67 will move over dead center position of pin 43. When that happens the springs 67 will return toward their normal state thereby causing the spring ends hooked in the eyes 62 of lever 60 to lift the yoke 61 in a clockwise direction, from the position shown in Fig. 1 to that shown in Fig. 2. This causes the springs to snap over center position. Consequently the loop 64 moves to the left causing the surface 64b of loops 64 to engage the lugs 56 to move the sleeve 33 to the left. When that happens the contacts 27, 28 will separate due to action of spring 31 which urged the arm 29 to the left, and the starting field exciting winding will be disconnected. When the centrifugal movement has gone far enough the surfaces 46 will contact the stop 48, stopping the rotational movement of the cradle 44 in a counterclockwise direction.

As the motor speed is reduced to a predetermined degree the spring 50 will overcome the effects of centrifugal force and move the cradle 44 clockwise about the pin 43 and as the same approaches its normal position the springs 67 will snap past dead center position and the surface 47 will engage stop 48, stopping the rotational movement of the cradle 44 in a clockwise direction as viewed in Fig. 2. When the spring snaps past dead center the surface 64a of loop 64 will bear against the lug 46 to urge the sleeve to the right to close the contacts 27 and 28. Since the lever 60 is formed from music wire it will be apparent that less friction between the parts is had and that a greatly simplified centrifugal mechanism having toggle snap action features with the minimum number of parts is provided, that is, the supporting plate 40, cradle 44, weight 49, pin 43, spring 50, two springs 67, lever 60 and sleeve 33. This centrifugal mechanism not only permits ease in assembly, but also provides for the control of inward and outward movements of the weights.

The lower portion of the plate 40 as viewed in Figs. 1, 2 and 5 has angular portions 70 to provide vanes which set air in motion for the purpose of cooling the motor.

While the embodiment of the present invention as herein disclosed, constitutes a preferred form, it is to be understood that other forms might be adopted.

What is claimed is as follows:

1. A centrifugal mechanism for controlling a switch comprising a rotatable shaft; a plate having its central portion fixed to the shaft; a sleeve adapted for sliding axial movement on the shaft for operating the switch; extensions associated with the sleeve; a cross-pin carried by the plate; a weighted member pivoted on the cross-pin and adapted for pivotal movement under centrifugal

force; a U-shaped lever having a yoke and a pair of arms formed from a single length of stiff wire having its arms pivoted on the cross pin, said arms having loop portions engaging the extensions on the sleeve for actuating same; and spring means connected with the weighted member and the yoke of the lever adapted to move to either side of the axis of said cross-pin for causing snap action of said sleeve; and single stop means formed integral with the plate for limiting the movements of the weights in either direction of its travel.

2. A centrifugal mechanism for controlling a switch and adapted for use on one end of a rotatable shaft, said mechanism comprising; a support form of relatively thin-metal having its central portion secured to the shaft; a sleeve having diametrical lugs on its outer surface adapted for sliding axial movement on the shaft; a cross member carried by the support on one side of the shaft; a weighted member pivoted on the cross member, said weighted member being adapted for pivotal movement under action of centrifugal force; a U-shaped lever having a yoke and a pair of arms formed from a single length of relatively stiff wire located on said mentioned side, each arm having a loop portion embracing a respective lug of the sleeve and having a hooked end pivoted to the cross member; and spring means located on opposite sides of the support and having one end connected with the weight member and having the other end connected with the yoke of the lever, said spring means being adapted to move to either side of the cross member for causing snap action to said lever and sleeve.

3. A centrifugal mechanism for operating a switch, and adapted for use on a rotatable shaft, said mechanism comprising a plate of sheet metal having its central portion secured to the shaft; a sleeve of insulating material mounted on the shaft and adapted for sliding axial movement thereon for actuating the switch, said sleeve having a pair of diametrical lugs on its outer surface; a weighted member pivotally mounted on the plate on one side of the plate; spring means opposing the action of centrifugal force upon the weighted member; a U-shaped member having a yoke formed of music wire for shifting the sleeve, said member having a pair of loop portions, one of said loop portions being adjacent the extremities thereof pivoted on the pivot of the weight and having the other loop portion about the lugs; and spring means movable to and fro across the dead center of the pivot for the weight said spring having one end connected to the weighted member and having the other end connected with the yoke of the U-shaped member and operable to move the lever about its pivot so as to move the sleeve from the movable contact with the outward swing of the weighted member; stop means on the plate for limiting the swing movements of the weighted member in either direction.

4. A centrifugal mechanism for operating a switch and adapted for use with a rotatable shaft, said mechanism comprising a plate of sheet metal having its central portion fixed to the shaft; a sleeve of insulating material adapted for axial movement on the shaft, said sleeve having a pair of integral diametrical lugs on its outer surface; a weighted member pivotally mounted on the plate and on one side of the shaft; spring means opposing the action of centrifugal force upon the weighted member; a U-shaped lever having a

yoke and a pair of arms for shifting the sleeve, said arms being formed with loops intermediate its end for embracing the lugs, and with eyes at their ends for pivotal connection with the pivot of the weighted member, said yoke being formed with eye offset portions beyond the normal plane of the arms; a pair of springs, each spring having one end connected with the weight member and having its other end connected with an eye offset portion and located below the dead center of the pivot of the weight member, said springs operating to shift the lever with a snap action when same are moved past dead center for the weights when the weights are under the action of centrifugal force.

5. A centrifugal mechanism for controlling a switch and adapted for use on one end of a rotatable shaft, said mechanism comprising; a support formed of relatively thin sheet metal having its central portion secured to the shaft; a sleeve of insulating material adapted for sliding axial movement on the shaft for operating the switch, a cross pin supported by the plate on one side of the shaft; a cradle weight member having its arms pivoted on said pin, said weight member being adapted for pivotal movement under the action of centrifugal force; a U-shaped lever having a yoke and a pair of arms formed of a single length of music wire straddling the support and cradle and having its arms pivoted on the cross pin, portions of said arms being adapted to engage portions of said sleeve; for actuating the sleeve and spring means connected with cradle and the yoke adapted to move to either side of the dead-center of the cross pin for causing snap motion to said sleeve.

6. A centrifugal device comprising; a plate adapted to be rigidly secured to a shaft; a sleeve having lateral extensions thereon and movable between positions relative to the plate on the shaft; a stop means associated with the plate; a weight member pivotally supported on the plate and presenting a pair of spaced stop surfaces disposed on opposite side of the stop for limiting angular movement of the weight relative to its pivot; a lever having connected arms disposed on opposite sides of the sleeve, said arms having one end pivoted on the pivot of the weight member and having an intermediate portion operatively connected with the extensions for actuating the sleeve; spring means connected with the weight and the lever for normally urging one of the stop surfaces against the stop and simultaneously causing the lever to move the sleeve to one of its positions while the other stop surface is adapted to contact the said stop for limiting the out movement of the weight when under the influence of centrifugal force; and contact means controlled by the sleeve.

7. A centrifugal mechanism for controlling a switch comprising; a plate adapted to be attached to a shaft; a sleeve having diametrical external lugs adapted for sliding movement on the shaft; a weighted member pivoted on said plate, said member being adapted for angular movement under action of centrifugal force; a U-shaped lever, each arm pivoted on the plate and having a portion for receiving a respective lug; spring means connected with the weight member and the lever, said spring being adapted to move to either side of the pivot for the lever for causing snap action of the lever and sleeve.

8. In a centrifugal switch, a lever member formed of a single length of music wire and

comprising a yoke and arms, said arms being formed with loops intermediate its ends for receiving extensions of a movable member and with eyes at their free ends for pivotal connection with a pivot for the lever.

9. In a centrifugal device, a plate having an integral stop rotatable with a shaft; a cross member supported by the plate on one side of the shaft; a weighted member pivotally supported on the cross member, said weighted member having a portion provided with a notch straddling the stop, said notch presenting stop surfaces equally distant from the cross member, said stop surfaces adapted to engage the stop for limiting the angular movement of the weighted member in either direction. 10

10. In a centrifugal device, a plate carrying a stop and a pair of spaced ears rotatable with a shaft, a cross rod supported by the ears; a weighted member pivotally supported on the rod.

said weighted member having a portion provided with a notch straddling the stop, said notch presenting stop surfaces equally distant from the rod, said stop surfaces adapted to engage the stop to limit the angular movement of the weighted member relative to the plate in either direction.

WALTER D. HARRISON.
